UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed June 5, 1922. Serial No. 565,822.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to rail anchoring devices of the character adapted to grip a rail 10 and abut against a stationary part of the road-bed, to resist the tendency of the rail to creep longitudinally in the direction of the traffic.

An object of the invention is to provide 15 an improved one-piece anchor that will be inexpensive to manufacture, that will take a combined spring grip and shackle hold on the base of a rail; that will increase its grip on opposite edges of the rail base during the 20 presence of any creeping movement of the rail; that will maintain its maximum spring grip on the upper and lower surfaces of the rail base; and that will be easy of application to or removal from a rail.

25 A more specific object of the invention is the provision of a rail anchor embodying the new and improved constructions and operations hereinafter described and claimed for carrying out the above objects, and such 30 other objects as will appear from the following description.

The invention is illustrated in a preferred embodiment in the accompanying drawings, wherein like characters of reference designate 35 like parts, and wherein—

Fig. 1 is a fragmentary plan view of a railroad rail and cross tie, showing a rail anchor constructed in accordance with my invention applied in its operative position 40 on the base flange of said rail.

Fig. 2 is a side view of the rail anchor shown in Fig. 1, the rail to which it is applied being shown in section.

Fig. 3 is a view similar to Fig. 2, showing the position assumed by the anchor device during its application to a rail; and

Fig. 4 is a view in perspective of the rail anchor device illustrated in the preceding figures.

50 In the drawings I have shown my improved rail anchor applied on the base flange of a railroad rail 10, in a position to abut against a cross-tie 11.

The anchor is made from a single bar of

steel, preferably round in cross-section, and 55 is bent to provide means for engaging opposite edges of the rail base and means which exert spring pressure against the upper and lower surfaces of the rail base. The anchor, preferably, comprises a body portion 12 60 which extends across the rail base, formed at one end with an upstanding portion 13 adapted to engage one edge of the rail base, and provided adjacent the other edge of the rail base with a double hook-shaped jaw portion 14 which projects over the upper surface 65 of the rail base. The jaw 14 consists preferably of substantially parallel portions 15 and 16, connected by means of a lateral bend 17. The portion 16 terminates in a relatively 70 large semicircular arm 18, providing means for bearing against a vertical face of the cross-tie 11. The extremity 19 of the tie-abutting portion also bears against the under surface of the rail base, preferably adjacent the vertical center of the rail. The vertical distance between the bearing point 21 of the double jaw 14 and the extremity 19 75 of the tie abutting portion 18 is normally less than the thickness of the rail base to which 80 the anchor is intended to be applied. With this construction the bearing surfaces 21 and 19 will be forced apart when the double hook portion 14 is forced upon the inclined surface of the rail base, and will thereby 85 exert a spring grip on the upper and lower surfaces of a rail base.

The distance between the surfaces 22 and 23 (Fig. 1), is normally greater than the width of the rail, so that the body portion 90 12 will assume a position diagonally across the rail base, and thereby effect a firm shackle grip on opposite edges of the rail when the anchor is in its applied position. The tie abutting portion 18 is preferably 95 disposed at an angle to the body portion 12 so that the tie abutting portion will bear flatwise against the tie when the body portion 12 is in its normal diagonal position. The body portion 12 is preferably bent 100 downwardly, as indicated by the reference character 24, so as to provide an anchor in which the body portion 12 will be subjected to a minimum distortion during the application of the device to a rail.

In applying the anchor to a rail, the double hook portion 14 is fitted over one of the base flanges of the rail base, substantially

as shown in Fig. 3 of the drawing. The anchor is then driven transversely of the rail until the abutment 13 clears the edge of the rail base at which time the spring 5 tension, to which the body portion 12 and hook portion 16, have been subjected, will move the abutment 13 upwardly into engagement with the vertical edge of the rail base. The portion 16 of the jaw 14 and 10 the tie abutment 18 are also tensioned during the application of the anchor to the rail, and will exert their maximum spring force against the upper and lower surfaces of the rail base when the anchor is in its applied 15 position. The abutment end 18 may then be driven toward the cross tie until the body portion 12 extends diagonally across the rail and the surfaces 22 and 23 (Fig. 1) 20 are in firm engagement with opposite edges of the rail base.

The novel features generic to this invention and to the invention disclosed in my copending application Serial No. 565,821 filed June 5, 1922, are claimed in said co- 25 pending application.

I claim:

1. A one-piece rail anchor formed with means for engaging opposite edges of the base of a rail, and with a portion adapted 30 to bear against a cross-tie; said tie-abutting portion being bent to provide a spring, the extremity of which bears against the under surface of the rail base.

2. A one-piece rail anchor formed with 35 means for engaging one edge of a rail base, and with a jaw portion which bears against the upper surface of said base and terminates in a tie abutment, the extremity of which bears with spring pressure against the bottom of the rail.

3. A one-piece rail anchor formed with means for engaging one edge of a rail base, and with a jaw portion which bears against the upper surface of said base and terminates in a tie abutment, the extremity of which engages the under surface of the rail; the vertical distance between said jaw and the extremity of said tie abutment being normally less than the thickness of the rail base, whereby said jaw and said abutment are distorted when the anchor is in its applied position, and exert a spring grip on the upper and lower surfaces of the rail base.

4. A one-piece rail anchor formed with means for engaging opposite edges of a rail base with a shackle hold, and with a jaw portion which bears against the upper surface of said base and terminates in a tie abutment, the extremity of which engages the under surface of the rail; the vertical distance between said jaw and the extremity of said tie abutment being normally less than the thickness of the rail base, whereby said jaw and said abutment

are distorted when the anchor is in its applied position and exert a spring grip on the upper and lower surfaces of the rail base.

5. A one-piece rail anchor formed with 70 means for engaging one edge of a rail base and with a double jaw portion which bears against the upper surface of said base and terminates in a tie abutment, the extremity of which bears against the under surface of 75 said rail.

6. A rail anchor composed of a bar provided at one end with means for engaging one edge of a rail base, formed intermediate 80 its ends with a hook shaped bend providing a resilient jaw for engaging the upper surface of the rail base at the other side of the rail, and terminating in a curved tie abutment adapted to be distorted to exert a spring grip on the rail when the anchor is 85 in its applied position.

7. A rail anchor composed of a bar provided at one end with means for engaging one edge of a rail base, formed intermediate 90 its ends with a hook-shaped bend providing a resilient jaw for engaging the upper surface of the rail base, at the other side of the rail, and terminating in a curved tie abutment, the extremity of which bears with spring 95 pressure against the under surface of the rail base when the anchor is in its applied position.

8. A rail anchor composed of a steel bar, round in cross-section, provided at one end 100 with means for engaging one edge of a rail base, and formed intermediate its ends with a hook-shaped bend providing a resilient jaw for engaging the upper surface of the rail base at the other side of the rail and terminating in a curved tie abutment adapted 105 to be distorted to exert a spring grip on the upper and lower surfaces of the rail base when the anchor is in its applied position.

9. A rail anchor composed of a steel bar 110 provided at one end with means for engaging one edge of a rail base, formed intermediate its ends with a hook-shaped bend providing a resilient jaw for engaging the upper surface of the rail base at the opposite side of the rail, and terminating in a curved tie abutment adapted to be distorted during the application of the anchor to a rail; said tie abutment being so formed 115 as to be subjected to the greatest distortion when the anchor is in its applied position.

10. A rail anchor comprising a spring bar provided at one end with means for engaging one side of the base of a rail and at the other with a jaw to engage the other side of the rail base which is formed with a curved arm extending around and spaced from the edge of the rail base and bearing against the under side thereof.

11. A rail anchor comprising a spring 120

bar provided at one end with means for engaging one side of the base of a rail and at the other with a jaw to engage the other side of the rail base which is formed with a curved arm extending around and spaced from the edge of the rail base with its extremity upturned and bearing against the under side thereof.

12. A rail anchor comprising a spring bar provided at one end with means for engaging one side of the base of a rail and at the other with a jaw to engage the other side of the rail base which is formed with a curved arm extending around and spaced from the edge of the rail base with its extremity upturned and bearing against the under side thereof.

13. A rail anchor comprising a spring bar provided at one end with means for engaging one side of the base of a rail and at the other with an expansible jaw to engage the other side of the rail base which is formed with a curved arm extending around and spaced from the edge of the rail base and bearing against the under side thereof.

14. A rail anchor comprising a spring bar provided at one end with means for engaging one side of the base of a rail and at the other with a jaw to engage the other side of the rail base which is formed with an extension adapted to bear with spring pressure upon the rail to flex the top of the

jaw down upon the upper surface of the rail base.

15. A rail anchor consisting of a metal bar, one end of which is provided with means for engaging one edge of the base of a rail, an intermediate portion of which is bent to form means for engaging the other edge of said rail base and the other end of which is adapted to intervene between said rail engaging means so as to be depressed when the anchor is applied to the rail to produce spring action in the grip of the anchor on the rail.

16. A rail anchor formed from a bar bent intermediate its ends to provide two legs, one of which is bent to provide a hook-shaped jaw to engage one edge of a rail base and the other providing a spring member adapted to bear at its extremity against the under surface of the rail base.

17. A rail anchor composed of a metal bar bent upon itself to provide two legs, one of which extends across the under surface of a rail base and is formed with a hook-shaped jaw portion adapted to engage the upper inclined surface of a rail base at one side of the rail, the other of said legs being bent to project under the rail base and bearing at its extremity against said under surface of the base adjacent said hook-shaped jaw.

ROLANDIS A. BLAIR.
